(57) **CLAIM**

The ornamental design for a steering wheel, as shown and described.

DESCRIPTION

This application contains subject matter related to the following co-pending U.S. design patent applications:

Application Ser. No. 29/413,268, filed herewith and entitled “Portion of a Vehicle Interior”; and

Application Ser. No. 29/413,271, filed herewith and entitled “Portion of a Vehicle Interior”.

FIG. 1 is a left, front perspective view of a steering wheel according to our design;

FIG. 2 is a right, front perspective view thereof;

FIG. 3 is a front view thereof;

FIG. 4 is a top view thereof;

FIG. 5 is a right side view thereof;

FIG. 6 is a left side view thereof; and,

FIG. 7 is a bottom view thereof.

The broken lines are for illustrative purposes only and form no part of the claimed design.
